UNITED STATES PATENT OFFICE.

JOHN P. SIMMONS, OF SAN FRANCISCO, CALIFORNIA, ASSIGNOR TO
SQUIRE V. MOONEY, OF SAME PLACE.

AIR-COMPRESSOR.

SPECIFICATION forming part of Letters Patent No. 635,517, dated October 24, 1899.

Application filed February 23, 1898. Serial No. 671,379. (No model.)

To all whom it may concern:

Be it known that I, JOHN P. SIMMONS, a citizen of the United States, residing at San Francisco, in the county of San Francisco and State 5 of California, have invented certain new and useful Improvements in Air-Compressors; and I do hereby declare the following to be a full, clear, and exact description of the same.

The invention relates to the class of machines for compressing air and other compressible fluids, and it refers particularly to the power connection between the compressor-piston and the motor-piston.

The object of the invention is to provide a simple, compact, and efficient compressor. I attain this object by means of the devices illustrated in the accompanying drawing, which is a side elevation of my invention, portions being shown in section to more clearly 20 illustrate it.

Referring to the drawing, A is the motor-cylinder, and A' is its piston-rod.

B is the compressor-cylinder, and B' its piston-rod.

C is a connecting-rod of the motor-cylinder piston-rod A' and crank-shaft. From this rod C, near one of its ends, projects an arm c, forming, with rod C, a bell-crank. To this projecting arm c is suitably connected to be 25 driven thereby the compressor piston-rod B' of the compressor-cylinder B.

The crank-shaft D is provided with a suitable fly-wheel E and is journaled in a suitable frame or bed-plate.

30 The arrangement thus described transmits from the power-piston motion to the com-

pressor-piston of a peculiar character, whereby the motive power is applied in most desirable way, in that at the time when compression is most intense the direct action of the steam is applied to compression instead of, as is usual, applying power stored up in the fly-wheel. In other words, the piston of the compressor reaches its extremes of reciprocation considerably ahead of the power-piston and while the power-piston is being impelled by the direct action of the steam and not while it is being carried over the "dead-center" by the momentum of the fly-wheel.

Having now described my invention, what I claim as new, and desire to secure by Letters Patent, is—

1. In a compressor a power-cylinder and a piston therein, a compressor-cylinder and a piston therein, a crank-shaft and a bell-crank connecting-rod connecting the power-piston crank and compressor-piston by its attachment to the bell-crank.

2. In a compressor a power-cylinder and a piston therein, a compressor-cylinder and a piston therein said cylinders being arranged with respect to each other, in the same vertical plane but their centers in different horizontal planes and a bell-crank connecting-rod connecting the power-piston and crank, and connecting the compressor-piston by its attachment to the bell-crank.

JOHN P. SIMMONS.
